CLAIM

The ornamental design for a combined wood duck box and nest bowl, as shown and described.

DESCRIPTION

FIG. 1 is a perspective view of the combined wood duck box and nest bowl showing our new design;
FIG. 2 is a front elevational view thereof;
FIG. 3 is a side elevational view thereof, the opposite side being a mirror image thereof;
FIG. 4 is a top plan view thereof;
FIG. 5 is a bottom plan view thereof;
FIG. 6 is a rear elevational view thereof;
FIG. 7 is a perspective view of the wood duck box nest bowl;
FIG. 8 is a top plan view of FIG. 7;
FIG. 9 is a bottom plan view of FIG. 7;
FIG. 10 is a front elevational view of FIG. 7, the rear elevational view being a mirror image thereof; and,
FIG. 11 is a side elevational view of FIG. 7, the opposite side being a mirror image thereof.
